UNITED STATES PATENT OFFICE.

WILLIAM J. LYMAN, OF EAST HAMPTON, AND ALFRED E. LYMAN, OF WILLIAMSBURG, MASSACHUSETTS.

IMPROVEMENT IN COFFINS.

Specification forming part of Letters Patent No. 35,102, dated April 29, 1862.

To all whom it may concern:

Be it known that we, WILLIAM J. LYMAN, of East Hampton, county of Hampshire, and State of Massachusetts, and ALFRED E. LYMAN, of Williamsburg, county of Hampshire, and State aforesaid, have invented certain new and useful Improvements in the Mode of Construction and Finish of Wood Coffins; and we do hereby declare that the following is a full, clear, and exact description of the same, reference being had to the accompanying drawings, which form part of this specification, in which—

Figure 1 is a side elevation with part in section. Fig. 2 shows the lid inverted. Fig. 3 shows the case with the lid removed. Fig. 4 is a cross-section of the whole.

This invention relates to a new and improved mode of construction and finish of wood coffins, whereby an article is produced combining with the cheapness of wood the strength, efficiency, and impermeability of iron and the durability of stone.

To enable others to make and use our invention, we will proceed to the description thereof.

Referring to the drawings annexed, wherein the marks of reference correspond in all the figures, A A are the sides of the coffin. B is the bottom, and C is the top or lid.

Our improved coffin is constructed in any shape or manner of which wood is susceptible. It is strengthened by a series of vertical and lateral braces, D E F, fixed to the bottom B, sides A, and lid C, and also by a corresponding series of knees, 2 2 and 1 1. The former should form part of the vertical braces D on the sides and the lateral braces F on the bottom, and the latter, 1 1, form part of the lateral braces E on the lid. The outer edge of the knees 1 are grooved, so as to fit down on the vertical braces D, which have a cross-section of a V form in order to be adapted to said groove, and are also cut down to a shoulder, 6, which receives and sustains the end of said knee or knees. We sometimes form lips on the upper outer corners of the knees to reach over and set down on the top of the vertical braces, so as to prevent any tendency of the sides to spread apart. With the construction and arrangement of the several

braces as above set forth, the whole weight to be sustained by the coffin-lid is received on the lateral braces and transferred through the knees to the vertical braces D on the sides.

The several devices thus furnish a means of resistance and strength adequate to sustain any load that the lid may be required to support.

Over each seam or joint we form grooved recesses 4 4. These recesses we fill with any plastic cement that will become hardened and prevent the ingress of air or water at the seams. To cause the cement to be securely retained, the recesses have a larger capacity or area than the width of the aperture leading into them. When the cement is sufficiently hardened, we lay on a thick coating of a compound consisting of four parts shellac and two parts india-rubber dissolved in naphtha or any suitable menstruum. We then embed in this compound an outer coating of sand, emery, pulverized quartz, or any like granulated or comminuted substance of metallic or silical nature. When the compound is hardened, the same process is repeated until the required thickness of the stony or metallic covering is attained. The dissolved gum or its equivalent renders the coffin entirely impermeable, and the granulated material aforesaid imparts a uniform and handsome finish, affords a protection to the said impermeable coating, and greatly enhances the durability of the whole, rivaling, if not surpassing, that of iron or stone.

On the under side of the coffin-lid, near the outer edge or margin thereof, we fix a thin tongue, 3. We groove the upper edge of the sides A and ends of the case, and the tongue 3 is arranged on the lid so as to sit into one side of said groove. The latter is filled with cement and has its bottom curved, as shown in the drawings, so that the pressing of the tongue into the groove will have the effect of forcing out part of the cement and throw it up on the surface of the edge of the sides A. The cement thus fills the seam at the junction of the lid with the sides completely. When screws are used to fasten on the lid, they should pass down on the outside of the tongue 3 into and through the cement.

We sometimes coat the sections of wood

before framing up the coffin, using for that purpose the aforesaid or any other preservative liquid or compound. In some cases we insert strips of india-rubber in the recesses around the seams. The india-rubber may be cut from the sheet or may be in the form of cord or tubing, and is embedded in the cement with which the recess is filled.

For the purpose of more perfectly securing the lid to the body or case, we make use of angular plates 5. (Shown in Figs. 1 and 4.) These are screwed fast to the lid, and, reaching down the sides, are secured thereon in a similar manner or otherwise. These plates embrace the corners closely and serve the purpose, in connection with the braces D and E and knees 1, of bracing and strengthening the case.

In handling coffins it sometimes happens that the weight of their contents causes the fastening of the handles to give way. To

prevent this we secure the handles by bolting or screwing them fast to one of the inside braces, as seen in Fig. 4. In such cases the said braces are arranged so as to accommodate the required position of the handles.

We generally make the braces of metal.

We make use of any liquid or compound of a preservative nature as a means of coating the wood and holding the outer coating or granular material, using varnish, oil paint, or any other adapted to the purpose.

Having thus described our improved coffin, what we claim as our invention, and desire to secure by Letters Patent, is—

The improved coffin, substantially as herein described, as a new article of manufacture.

WM. J. LYMAN.
ALFRED E. LYMAN.
